UNITED STATES PATENT OFFICE.

RUSSELL B. KINGMAN, OF WEST ORANGE, NEW JERSEY, ASSIGNOR TO METAL TEXTILE CORPORATION, OF WEST ORANGE, NEW JERSEY, A CORPORATION OF RHODE ISLAND.

ABRASIVE POT-CLOTH FABRIC.

Application filed April 25, 1925. Serial No. 25,826.

To all whom it may concern:

Be it known that I, RUSSELL B. KINGMAN, a citizen of the United States, residing at West Orange, in the county of Essex and 5 State of New Jersey, have invented certain new and useful Improvements in Abrasive Pot-Cloth Fabrics; and I do hereby declare the following to be a full, clear, and exact description of the invention, such as will 10 enable others skilled in the art to which it appertains to make and use the same, reference being had to the accompanying drawings, and to characters of reference marked thereon, which form a part of this specification.

This invention relates to improvements in abrasive fabrics; and the invention has reference, more particularly, to a composite vegetable yarn and metallic fabric suitable 20 for use in the manufacture of pot-cloths, scouring-mits and similar articles.

To provide a fabric suitable for use as an abrasive pot-cloth or scouring cloth, it is highly desirable that the body of the cloth 25 be absorbent so that it will readily take up and hold water or other cleansing fluid, and it is also highly desirable that the abrasive elements of the cloth shall be exposed at the working surface or face of the cloth to the 30 greatest extent or degree possible, so that a maximum amount of the abrading element may be easily brought into effective scrap- ing or abrading contact with the surface to be cleaned when applying the cloth thereto.

Heretofore it has been the practice to produce an abrasive fabric for pot-cleaners by winding or gimping cotton yarn, jute or other vegetable fiber strands with a metallic wire such as copper, and then either weaving 40 or knitting such metal gimped yarns into an open mesh fabric. Abrasive fabrics so constructed provide but a minimum amount of vegetable yarn, and consequently possess but a limited capacity for absorbing and 45 holding water or other cleansing fluid; and, furthermore, the gimping or winding of the metallic wire about the yarn requires a considerable quantity of such metallic wire to be used, less than half of which is effective 50 at the outer face of the fabric for an abrading function.

It is the object of the present invention to provide a composite vegetable yarn and metallic fabric suitable for abrasive pot- 55 cloths, in which the vegetable yarn, both in

quantity and in relation to the fabric as a whole, is arranged to provide for a maximum absorption and retention of water or other cleaning fluid, and in which the disposition and arrangement of the metallic 60 element of the fabric is such that a maximum amount of the same is exposed so as to project from the working surface or face of the fabric. To such ends my present invention comprises, a knitted fabric composed of 65 one or more vegetable yarn threads and a metallic thread, the latter consisting, preferably, of a flat ribbon-like copper wire or strand, the same being interknit to provide a ribbed fabric, with the vegetable yarn 70 predominating in exposure at the rear face or back of the same, and the metallic element forming rib-like portions exposed at and projecting from the front or working face of the same.

The invention is clearly illustrated in the accompanying drawings, in which:—

Figure 1 is a plan view of the front or working face of the novel abrasive fabric made according to and embodying the principles of this invention; Figure 2 is a plan view of the rear face or back of the novel fabric; Figure 3 is a plan view of the front or working face of the fabric, drawn on a considerably enlarged scale; Figure 4 is a 85 transverse section, taken on line 4—4 in Figure 3.

Figure 5 is a fragmentary perspective of the fabric, looking toward the front or working face thereof, and illustrating the manner of interlooping or knitting the vegetable yarn and metallic strands together to form the fabric; and Figure 6 is a similar view looking toward the rear face or back of the fabric.

Figure 7 is a perspective view, showing the knitted relation of the vegetable yarn threads when employing double yarn; and Figure 8 is a plan view, showing the knitted relation of the vegetable yarn threads when employing a single yarn.

Similar characters of reference are employed in all of the hereinabove described views to indicate corresponding parts.

Referring now to said drawings, the novel 105 fabric consists of a vegetable yarn Y, preferably in the form of a double yarn thread as shown in Figures 1 to 7 inclusive, or if desired, in the form of a single yarn thread as shown in Figure 8, with which is knit a 110

metallic thread M. The vegetable yarn Y may be made of cotton, jute, or other vegetable fiber, while the metallic thread is preferably made of copper or other non-corrosive 5 metal. The yarn thread Y is so knitted as to provide rows of loops; alternate loops 10 of each row are interknit or interlocked with corresponding loops 10 of the succeeding row, thus leaving in each row free loops 11 10 intermediate the interlocked loops 10. The metallic thread M is likewise knitted to provide rows of loops; alternate loops 12 of each row are interknit or interlocked with corresponding loops 12 of the succeeding 15 row, thus leaving in each row free loops 13 intermediate the interlocked loops 12. In knitting together the yarn thread Y and metallic thread M, the interlocked loops 12 of the latter are carried over and interlocked 20 with the free loops 11 of the former, while at the same time the interlocked loops 10 of the yarn thread are carried beneath and interlocked with the free loops 13 of the metallic thread. In this manner a 25 knitted fabric of the rib type is produced in which the metallic thread M is massed in the form of projecting ribs at the front or working face of the fabric, thus exposing a maximum quantity of metal in extension 30 from the working face of the fabric, while the yarn thread Y is massed at the rear face or back of the fabric, thus providing a fluid absorptive element to hold a cleaning fluid which, when the cloth is used will be exuded 35 from the face of the fabric to soften dirt, grease or the like while the metallic element is producing the desired abrasive or scouring effects. A maximum abrasive effect is obtained if the metallic element of the fabric 40 is in the form of flat ribbon-like wire, since such form of wire or thread, when looped and interknit into the body of the fabric, produces wherever exposed at the working face of the latter, a plurality of chisel-like 45 edges or scraping points which are most efficient in form for the purposes in view; however, where a milder abrasive action is desirable round metallic wire or thread may be employed. 50 While I have described above one manner of interknitting the yarn and metallic threads to produce the novel pot-cloth fabric, I do not necessarily limit myself to such particular method as to its production, but 55 conceive my present invention to embrace

any suitable method of knitting or weaving, so long as it produces the desired preponderance of exposed metallic element at the working face of the cloth, and at the same time provides a substantial body of vegetable yarn adapted to attain the desired maximum water absorption and retention characteristics. 60

Having thus described my invention, I 65 claim:

1. An abrasive pot-cloth fabric comprising interknit vegetable yarn and metallic threads so combined that the former provide a fabric body adapted to readily absorb and retain cleansing fluids while the latter are 70 disposed to provide rib-like abrasive elements exposed on and projecting from the working face of said fabric body.

2. An abrasive pot-cloth fabric comprising knitted vegetable yarn thread to form 75 the body of the fabric and metallic threads interknit with said yarn thread so as to provide a preponderance of metallic material exposed on the working face of the fabric 80 body.

3. An abrasive pot-cloth fabric comprising vegetable yarn material knitted to provide rows of alternate interlocked and free loops, and metallic material also knitted to provide rows of interlocked loops interengaged with said free loops of vegetable yarn whereby the bulk of the metallic material is connected with and disposed upon the outer working face of the fabric. 85

4. An abrasive pot-cloth fabric comprising 90 interknit vegetable yarn and metallic materials so combined as to form a rib-knitted fabric whereby the yarn material produces surface ribs at the rear face of the resultant fabric and the metallic material produces 95 surface ribs at the front or working face of the fabric as and for the purposes described.

5. An abrasive pot-cloth fabric comprising 100 vegetable yarn material knitted to provide rows of alternate interlocked and free loops, and flat ribbon-like metallic strands also knitted to provide rows of interlocked loops interengaged with said free loops of vegetable yarn whereby said metallic loops are exposed to project from the outer working 105 face of the resultant fabric.

In testimony that I claim the invention set forth above I have hereunto set my hand this 25th day of April, 1925.

RUSSELL B. KINGMAN.
